Attorney.

UNITED STATES PATENT OFFICE

CONRAD SAUER, OF PITTSBURGH, PENNSYLVANIA, ASSIGNOR OF FIFTY PER CENT TO
JOHN G. DOELFEL, OF PITTSBURGH, PENNSYLVANIA

CLOTHES PROP

Application filed March 11, 1930. Serial No. 434,901.

My invention relates to clothes props, and more particularly to clothes-line holding devices therefor.

One object of my invention is to provide a line-holding device for clothes props whereby a positive engagement between the prop and a clothesline will be insured.

Another object of my invention is to provide a line-holding device of improved form which may be easily attached to various types of existing clothes props.

Still another object is to provide a clothes prop with a line holding device which will be effective to hold the clothes line securely, and to grip the line so as to prevent sliding movement of the prop along the line.

One form which my invention may take is shown in the accompanying drawings, where in Figure 1 shows a clothes-prop with its upper end shown in vertical section, with the line holder supported in the end of the prop; Fig. 2 is a transverse sectional detail of the upper end of the prop; Fig. 3 is a plan view thereof, and Fig. 4 is a fragmentary end view 25 of the line holder.

A prop 4 of any suitable length is provided with a pointed lower end so that it may more readily enter the ground when in use. A clothes-line holding device 5 is secured to the upper end of the prop.

The holding device 5 is preferably formed of a single piece of spring wire which is suitably bent, as hereinafter described, to form a pair of spaced jaw members 7 and 8, each 35 jaw having cooperating side members or prongs 10 and 11, that serve to receive and clamp a clothesline 9. The jaws 7 and 8 are spaced apart longitudinally of the line, so that the prongs 10 and 11 of the jaw 7 will 40 grip the line at one point and the prongs 10 and 11 of the jaw 8 will grip the line at another point. The upper ends of the jaws 7 and 8 are flared outwardly, forming between them a line receiving throat 12.

One end of the wire is provided with a threaded portion 6 and the other end of the wire is bent to form a washer-like eyelet 13 through which the threaded portion 6 is extended. By means of the threaded end portion 6, the holding device may be easily and

conveniently secured to the end of a prop or pole, the eyelet 13 serving as a seat for rigidly supporting the device thereon. As shown more clearly in Fig. 4, the eyelet 13 is provided with a down-turned lip 15, the eyelet serving as a lock washer to retain the holder against accidental removal from the prop.

In one manner of conveniently making my holding device, the wire may be bent to form a substantially V-shaped loop having a closed upper end, the sides of the loop thus formed constituting the prongs 10 of the jaws 7 and 8. The wire may then be bent downwardly to form an inverted U-shaped member having parallel sides 11 and the mediate V-shaped loop therebetween, the sides 11 being alternately opposed to the sides 10 of the loop. In this manner, the spaced jaws 7 and 8 will be formed, each having alternately opposed prongs 10 and 11. One end of the wire may be bent inwardly and downwardly to form the end portion 6 which may be threaded, and the other end of the wire may be bent around the end portion 6 to form the seat 13.

In using my device the line 9 enters the throat 12, between the upper ends of the prongs 10 and 11, which are normally closed together, as shown in Fig. 4, instead of spread apart as in Fig. 1, and is forced downwardly between the prongs of the jaws 7 and 8. The prongs of the jaws yield sufficiently to permit the line entering between them to a point where the line will be securely gripped.

Due to the mediate V-shaped loop, the line will be kinked between the alternate prongs of the spaced jaws, thereby positively securing the line and preventing sliding movement of the prop along the line, (Fig. 3). To further accentuate the gripping action of the jaws, I prefer to flatten the prongs 10 and 11, so that the line will be subjected to gripping pressure over a greater area of its length. Also, the prongs 10 and 11 may be formed with longitudinally-extending grooves or corrugations 14 to increase their holding action on the line.

It will be noted that my clothesline-holding device provides a compact unitary struc-

ture which may conveniently be attached to any suitable pole or any clothesprop at hand.

Furthermore, a line holder, embodying the principles of my invention, is particularly suitable for use on a wire clothes line, since the ordinarily smooth wire line will be kinked between the alternate flattened prongs of the spaced jaws which will prevent sliding movement of the prop along the line. Also, the corner edges of the flattened prongs will serve to more effectively engage the line to prevent sliding movement of the prop.

I claim as my invention:—

1. A line-holding device for clothes props, comprising a wire bent to double loop form, with the loops disposed in such relative relation as to constitute gripping jaws, and one end of the wire extending in a straight line and being screw-threaded to permit of it being screwed into a prop, the other end of the wire being bent around the said straightened end to serve as a stop member.

2. A line-holding device for clothes props, comprising a wire bent to double-loop form, with the loops disposed in such relative relation as to constitute gripping jaws, and one end of the wire extending in a straight line and being screw-threaded to permit of it being screwed into a prop, the other end of the wire being bent transversely at a point above the screw-threaded portion in position to seat against the surface into which the screw is driven.

3. A spring line-holding device for clothes props comprising a pair of spaced jaws formed from a continuous piece of wire bent to form substantially vertical side members in opposed relation and connected by an intermediate bent portion of V form that is diagonally disposed with respect to a line extending between the first-named side members.

In testimony whereof, I, the said CONRAD SAUER, have hereunto set my hand.

CONRAD SAUER.
